HIGHWAY BARRICADE

Kenneth A. Harding, Waltham, Mass.
(130 Bridge St., Newton, Mass.)

Filed Oct. 28, 1957, Ser. No. 692,770

7 Claims. (Cl. 256—64)

This invention relates generally to a highway barricade, and more specifically to a highway barricade of the foldable type.

With the present type of highway barricades now in use in this country, it becomes necessary when removing these barricades, to take them apart so as to facilitate storage and transportation thereof. Since these barricades are usually nailed or screwed together, taking them apart becomes a tedious and time-consuming task, which wastes many man-hours. Therefore, the primary object of this invention is to provide a highway barricade which may be quickly and easily folded into a storage or transportation position.

Another object of this invention is to provide a highway barricade which is of sturdy construction; and which may be locked in an open or a closed position.

A still further object of this invention is to provide a highway barricade having legs which are slidably and pivotally connected by a new and novel type of two-headed screw to be used in connection therewith.

A further object is to provide a barricade having springs for holding the legs in place which may hold the legs even though the two-headed screw should be removed, as would occur if the slots in the legs became clogged.

A still further object of this invention is to provide a device which is simple and inexpensive, yet exceedingly effective for the purpose for which it is designed.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a perspective view of the highway barricade comprising the present invention;

Figure 2 is an end elevational view taken upon an enlarged scale of the device illustrated in Figure 1, parts being broken away and certain concealed parts being shown in dotted lines;

Figure 3 is a vertical transverse sectional view taken on an enlarged scale substantially along the plane defined by reference line 3—3 of Figure 1;

Figure 4 is a horizontal sectional view taken substantially along the plane defined by reference line 4—4 of Figure 3;

Figure 5 is a vertical sectional view taken longitudinally through the highway barricade, parts being broken away;

Figure 6 is a vertical sectional view similar to Figure 5 but illustrating the legs in the folded position, and with the clamp in its retaining position of Figure 7;

Figure 7 is a vertical transverse sectional view taken substantially along the plane defined by reference line 7—7 of Figure 6, illustrating details of construction thereover; and

Figure 8 is a vertical sectional detail view taken sub-

2

stantially along the plane defined by reference line 8—8 of Figure 5.

Referring now more specifically to the drawings, the numeral 10 generally designates the highway barricade comprising the present invention. This barricade consists of a channel member 12, having a bight portion 14, and downwardly and outwardly inclined sides 16 and 18.

Inclined sides 16 and 18 have openings 20 formed in the lower corners thereof for a purpose which will be described below. Bight portion 14 has square shaped openings 22 formed therein for the reception of lights or other such ornaments as may be desired.

This device further consists of end portions 24 mounted inwardly of the ends of the channel member. Reinforcing plate members 26 are connected diagonally between the sides 16 and 18 and ends 24. In the enclosure formed thereby are mounted springs 28 with the upper ends 25 for a purpose to be described below.

Located inwardly of the sides 16 and 18 are strap members 30 and 32 which support a transverse support 34 which in turn supports a generally W-shaped clamp 36 pivoted to the support 34, and has curved extremities to lock the legs resiliently in place when they are folded. This pivotal connection is completed by means of a bolt 25 38 which passes through correspondingly aligned openings in the midportions of support 34 and clamp 36.

In openings 20, are inserted double-headed screws 40 which have an outer head 42, an intermediately disposed inner head 44, and a nut 46 for the threaded end therefor. Angular or L-shaped legs 48 having slots 50 in each end with a larger opening 52 communicating therewith, are locked to sides 16 and 18 slidably, by means of respective heads 42 and 44 being located on either side of the slots. Thus, the legs are slidably connected to the channel member. Since all of these legs are necessarily connected in the same manner, they will all be slidably and pivotally connected to the channel member as described above. Thus, it may be seen that when the legs are attached by means of their slots 50 to the channel member, they may be slidably inserted into a compartment formed therefor by plates 26, ends 24 and corresponding sides 16 and 18. The upper ends of legs 48 are so disposed in the housing that the springs 28 frictionally retain the legs therein, and since these legs are downwardly divergent, a stable support is provided for the channel member. Thus, it may be seen when all the legs are in this position a proper and stable barricade has been formed.

In the event that the slots become clogged and sliding of the leg on the two-headed screw 40 prevented, springs 50 28 are of such a construction and strength that the screw 40 may be removed and the legs 48 will be held in position solely by these springs.

Now, when it is necessary to remove this barricade and move it to another place, it is only necessary to slide the legs out of the housing provided therefor, and pivot these legs about the screws toward the channel member, so that they lie substantially upon each other as illustrated in Figures 6 and 7. In this position, the clamp 36 may be used to yieldingly retain the legs in their folded position. It may be seen that the pivoted screw 40 is necessary for this device, in that it adapts the channel member to slidably and pivotally accommodate the legs thereon.

It may now be seen that I have shown and described a new and improved type of barricade which may be quickly folded into a storage position, which saves much time and effort. This may be especially realized when it is remembered that in the older type of devices when their removal and transportation became necessary, it has been a practice to completely disassemble these devices, and ship them or transport them in their disassem-

bled state. This resulted in a great wasting of time and effort, since with this new type of device it is merely necessary to slide the legs out of their housing and pivot them into a storage position.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. A highway barricade comprising a horizontal channel member having downwardly directed sides, a plurality of legs detachably connected to said sides, means detachably securing each leg to said channel member, said means comprising a two-headed fastener secured to one of said sides, each leg including a pair of slots at the opposite ends thereof, said fastener being slidably disposed in a selected one of said pair of slots with the sides of the leg being retained between the heads of said fastener, said slots having enlarged openings at their inner ends for passage of said fastener heads therethrough whereby to permit removal and reversal of said legs upon said fasteners.

2. A highway barricade comprising a horizontal channel member having downwardly directed sides, a plurality of legs detachably connected to said sides, means detachably securing each leg to said channel member, said means comprising a two-headed fastener secured to one of said sides, each leg having an elongated slot therein adjacent its upper end with the lower end of said slot being laterally enlarged to permit passage of said fastener therethrough, said fastener being slidably disposed in said slot with the sides of said leg being slidably retained between the heads of said fastener, a support strap extending transversely between said sides and secured thereto intermediate the ends of the latter, a clamp pivoted upon said support strap for engaging all of said legs in the pivotally folded position of the latter and retaining the legs within the channel member.

3. A highway barricade comprising a horizontal channel member having downwardly directed sides, a plural-

ity of legs detachably connected to said sides, means detachably securing each leg to said channel member, said means comprising a triangular pocket at each corner of said channel member between said sides and each pocket receiving one leg, said channel having a transverse end plate extending between and secured to said sides, diagonal brace plates having one end of each secured to said end plate and the other end of each secured to a side, said end plate, diagonal brace plate and a side associated therewith defining each pocket, a spring disposed in said pocket and secured to said diagonal brace plate and engaging a leg whereby to yieldingly urge the latter into frictional engagement with both said side and to said end plate.

4. The combination of claim 3 including two-headed fasteners carried by said sides, each leg having an elongated slot slidably receiving said fastener whereby to enable sliding movement of said leg for withdrawal of the latter from said pocket and pivotal movement of said leg about said fastener to a folded position beneath said channel member.

5. The combination of claim 1 wherein said channel member includes light emitting openings in its bight portion.

6. The combination of claim 3 wherein each leg has an elongated slot therein adjacent its upper end with the lower end of said slot being laterally enlarged to permit passage of said fastener therethrough, said fastener being slidably disposed in said slot with the sides of said leg being slidably retained between the heads of said fastener, a support strap extending transversely between said sides and secured thereto intermediate the ends of the latter, a clamp pivoted upon said support strap for engaging all of said legs in the pivotally folded position of the latter and retaining the legs within the channel member.

7. The combination of claim 6 including light emitting openings in the bight portion of said channel member.
